UNITED STATES PATENT OFFICE.

ARTHUR L. SMITH, OF PORTLAND, OREGON.

INTERNAL-COMBUSTION MOTOR.

1,336,392.

Specification of Letters Patent.

Patented Apr. 6, 1920.

Application filed October 7, 1918. Serial No. 257,284.

To all whom it may concern.

Be it known that I, ARTHUR L. SMITH, a citizen of the United States, and a resident of Portland, county of Multnomah, 5 State of Oregon, have invented certain new and useful Improvements in Internal-Combustion Motors, of which the following is a specification.

My invention relates to internal combustion motors in general, and particularly to 10 that type of such motors known as rotary motors.

The objects of my invention are to provide a motor of the rotary type requiring 15 no mechanical packing between the rotor and the stator; to eliminate all cooling devices; and to produce a motor of highest efficiency at high temperatures.

I accomplish the above objects and other 20 desirable results to be hereinafter described by means of the construction illustrated in the accompanying drawings, which are a part of this application for Letters Patent, like characters of reference indicating like 25 parts throughout the several views thereof, and in which:

Figure 1 is a plan view of my device.

Fig. 2 is an enlarged sectional elevation upon line 2-2 of Fig. 1.

Fig. 3 is an end elevation, parts being broken away.

Fig. 4 is a sectional elevation of the valves, upon line 4-4 of Fig. 3.

Fig. 5 is an elevation of the valve cam 35 wheel.

Figs. 6, 7 and 8 are longitudinal sectional elevations of the valve chambers illustrating the three positions of the valves.

Figs. 9, 10, 11, 12, 13 and 14 are diagrammatical sectional elevations to illustrate the 40 cycle of operations.

Fig. 15 is a modified form of mounting the units.

In general my invention consists of a pair 45 of housings with a bladed rotor mounted upon a rotating shaft in each housing, and valve controlled passageways therebetween.

Sufficient liquid, preferably water, is contained in said housings and passageways 50 to partially fill one of said housings, and the valves controlling said passageways are operated and timed to permit the flow of liquid therethrough synchronously with the cycle of operations now to be described.

55 In Fig. 9 the housing R is shown partially filled with liquid, 15 representing the re-

volving blades of the rotor, and the liquid is shown massed upon the sides of the housing or stator R by centrifugal force created by the revolution of the blades 15.

The liquid is revolving with the blades, and since the total amount of liquid is less than the volume of housing R a central space 16 is created, into which has been injected an explosive insoluble gas.

The valve at A is set to open the passageway between the housings R and L, and the gas is exploded by an electric spark. The valve at B being closed, the liquid in housing R, impressed by the expanding gas 70 in space 16, evacuates housing R by way of passageway and valve at A, and enters housing L therethrough.

The liquid enters housing L upon a tangent to the periphery thereof, and thereby 75 is caused to rotate therein, the rotation of the liquid causing rotation of the rotor blades 15 in housing L.

Previous to the entrance of the liquid into housing L a charge of explosive insoluble gas was injected therein, and the entrance of the liquid compresses said gas into a small space 17, as shown in Fig. 10.

The valve at A now moves to close its passageway into the housing L, and to open 85 its passageway into housing R to the atmosphere, as shown in Fig. 10, thereby allowing the products of combustion to escape from the housing R, while the liquid in housing L continues to rotate the rotor 90 blades 15 therein by its momentum.

The rotor blades 15 in housing R continue in rotation after the liquid has entirely evacuated said housing, and thereby the products of combustion therein are 95 caused to rotate with said blades, the centrifugal force thus produced helping to discharge said products of combustion through the passageway and valve at A.

The valve at A then moves to close the 100 passageway into each housing, as shown in Fig. 11, wherein the valves at both A and B are shown closing their respective passageways completely.

A charge of explosive insoluble gas is now 105 injected into housing R. The valve at B is then moved to open the passageway respective thereto, and the compressed gas within the space 17 in housing L is exploded by electric spark, thus driving the 110 liquid into housing R by way of passageway and valve at B, as shown in Fig. 12.

The liquid enters housing R tangentially at the periphery thereof, and thereby is caused to rotate within housing R, which rotation is imparted to the rotor blades 15 in said housing.

When the liquid has entirely evacuated housing L, the valve at B moves to close its passageway into housing R, and to open its passageway into housing L to the atmosphere, as shown in Fig. 13.

The products of combustion now are expelled from housing L through the passageway and valve at B, while the rotor blades 15 in housing R are rotated by the momentum of the liquid therein.

When the products of combustion have been expelled from housing L the valve at B closes its passageway entirely, and then a charge of explosive insoluble gas is injected into housing L, the rotor blades meantime being propelled by the momentum of the liquid in housing R, as shown in Fig. 14.

The valve at A then moves to the position shown in Fig. 9 and the cycle of operations is repeated.

It is evident from the foregoing that the power transmission element in my device is the liquid contained therein; it is also evident that this same liquid forms the packing between the rotor and the stator or housing; and it is further evident that since there are no close fitting moving parts exposed to the heat of the exploding gas, that no temperature limitation need be considered, and that therefore no cooling system need be employed. Indeed the only temperature limitation is the natural one of the temperature of super-heated steam, since the liquid will be raised to that temperature only.

Since steam will be generated in this device and carried away with the exhaust gases, it will be necessary to make provision therefor, and also for the replenishing of the liquid.

I accomplish this by leading the exhaust into a condenser wherein the steam is condensed, and wherefrom the condensed steam is returned as hot liquid to the housings.

The condensation of the steam produces a partial vacuum which greatly assists the evacuation of the housings by the products of combustion, and the return of hot liquid enhances the efficiency of the device over any cold liquid feed.

The condenser may be of any ordinary type known to the art, and since it is no part of my invention, it is not illustrated in the drawings.

The housings R and L may be mounted side by side as indicated in Figs. 9 to 14 inclusive, and the shafts of the rotors geared together as hereinafter described, or the housings may be axially alined upon the

same shaft and the passageways therebetween bent to suit, as illustrated in Fig. 15.

A preferred form of construction is illustrated in detail in the various figures of the drawings, which show the housings R and L formed of halves R₁ and R₂, and L₁ and L₂, said halves being flanged and connected by bolts, as shown in Fig. 2.

A hollow shaft 18 is rotatably mounted in bearings formed by the hubs of the housings, and ball bearings 19 are provided upon said shaft to take any end thrust that may be produced by the explosions of the gas within the housings.

The hollow shaft 18 of housings R and L respectively are connected by pinions 20 and idler gear 21 so that the shafts 18 run respectively synchronously.

Fixedly mounted upon each hollow shaft 18, and respectively within housings R and L, is a spider consisting of a hub 22 and a series of radially disposed parallel pairs of arms 23, or the equivalent thereof, each of said pairs of arms having mounted thereon an impeller blade 15.

The hub 22 and the hollow shaft 18 have registering orifices cut therein forming ports 24 communicating from the interior of said shaft to the interior of the respective housings, as shown in Fig. 2.

An intake valve 25 is mounted within one end of hollow shaft 18, which end of said hollow shaft communicates with a fitting 26, which fittings are connected by a manifold to a carbureter. The manifold and carbureter being old and well known devices in common use are not illustrated in the drawings, as they form no part of my invention.

Within said hollow shaft 18, and opposite said intake valve 25 is mounted a low tension spark plug 27, as shown in Fig. 2. Said spark plug is fixedly mounted in a sleeve 28 which is longitudinally slidably and rotatably mounted within hollow shaft 18, as shown in Fig. 2.

Said sleeve 28 is secured to the hub of a thimble 29 which thimble is screwed upon the end of hollow shaft 18, whereby the turning of said thimble 29 moves the sleeve 28 longitudinally within hollow shaft 18. The purpose of such movement is to effect the closing of ports 24 by the adjacent end of sleeve 28 when the motor is shut down, thereby excluding moisture from the spark plug 27.

The thimble 29 is insulatingly bushed at 30, and the spark plug electric terminal 31 is projected beyond said thimble through said insulating bushing to contact with a spring conductor 32 which connects with a binding post 33, as shown in Fig. 2, the spark plug being grounded in the machine in the usual manner.

Each of said housings R and L are pro-

vided with flanged ports 34 and 35, as shown in Fig. 3, the former constituting passageways B and the latter the passageways A that are shown in Figs. 9 to 14 inclusive.

5 Mounted between the flanges of said ports are valve chambers 36, said valve chambers being connected integrally by a web 37 containing a bearing 38 for shaft 39, upon which shaft is secured gear 21, as shown in Fig. 4.

The valves referred to as at A and at B in Figs. 9 to 14 inclusive are mounted within said valve chambers 36, and each valve consists of a cylindrical portion 37 with a transverse port 38 therethrough, and an apron portion 39, as shown in Figs. 6, 7 and 8. The valve port 38 is adapted to connect ports 34 and 35 respectively, as shown in Fig. 6, and also in Fig. 3, where one valve chamber is sectioned; cylindrical portion 37 is adapted to close each of the ports 34 and 35, as shown in Fig. 7; and the apron portion 39 is adapted to close only one of the ports 34 or 35, leaving the other port open 25 into the valve chamber 36, as shown in Fig. 8.

The exhaust from the open port 34 or 35, as shown in Fig. 8, passes from valve chamber 36 to the atmosphere, or to the condenser 30 if one is used, through orifice 40.

A magneto and commutator or timer may be mounted directly upon one end of shaft 39, or geared or bolted thereto, as convenient, for the purpose of generating electric current and distributing the same to the spark plugs synchronously with the cycle of operations. These devices being of ordinary construction and not a part of my invention are not illustrated in the drawings.

40 The valves in chamber 36 are operated by a cam wheel 41 secured to shaft 39 and co-acting with rollers 42 upon the valve stems 43, as shown in Fig. 4. Said cam wheel 41 is formed to operate the valves synchronously with the cycle of operations described in connection with Figs. 9 to 14 inclusive.

My device is started by rotating shaft 39 from some outside source of power, as an 50 electric starter or the like.

The power derived from my device is taken from shaft 39 by pulleys or gears thereon, as most convenient.

My device may be made of any size, and 55 constructed of any materials deemed convenient and suitable for a device of this character, and while I have illustrated and described a form of construction and arrangement of parts found desirable in materializing my invention, I wish to include in this application for Letters Patent all 60 mechanical equivalents or substitutes that may fairly be considered to come within the scope and purview of my invention as defined in the appended claims.

Having disclosed my invention so that others skilled in the art may be enabled to construct and to use the same, what I claim as new, and wish to secure by Letters Patent is:

1. In an internal combustion motor, a housing consisting of a pair of casings and connecting passageways therebetween; a liquid within said housing; means to cause said liquid to rotate within said casings alternately, and to circulate from one casing to the other through said passageways, the direction of circulation of said liquid within said housing being constant; and means within said housing whereby the combined circulation and rotation of said liquid produces power. 75

2. A rotary internal combustion motor having twin rotors and twin stators, in which the combustion of a gas within one of said stators operates the rotor within the other of said stators, the power transmission element being a liquid injected into said second stator from said first stator by said combustion therein. 90

3. In an internal combustion motor, a pair of stators; rotors within said stators; a liquid element initially within one of said stators and forming packing between the stator and respective rotor; means whereby the explosion of a gas within said stator containing said liquid element may forcibly eject said liquid from said stator and inject the same into the other stator, for the purpose of rotating the rotor within said latter 100 stator.

4. An internal combustion motor, comprising a stator, a rotor and a liquid within said stator immersing said rotor; the combustion chamber being the annular space entirely surrounding the rotor formed within the annular ring of liquid as the same is rotated and held upon the internal periphery of said stator by centrifugal force. 105

5. In an internal combustion motor: a combustion chamber casing containing a liquid; means to rotate said liquid and thereby to form an annular rotating ring thereof within said casing, the entire annular internal periphery of said rotating ring of which 110 liquid forming one wall of said combustion chamber within said casing; a discharge port in said casing through which port said liquid is forcibly discharged by exploding gas within said combustion chamber; and 115 means to utilize the power of said discharged liquid. 120

6. An internal combustion motor, wherein the combustion chamber is a space formed within a body of liquid; means to introduce 125 into said combustion chamber an explosive gas; means whereby the compression of said gas is accomplished by an increase in volume of said liquid within the stator constricting said combustion chamber; means to explode 130

said gas when said combustion chamber is sufficiently constricted, thereby expanding said combustion chamber; and means whereby the pressure within said liquid due to said expansion of the combustion chamber within the liquid may be utilized to produce power.

7. A casing with an annular peripheral side and an exit orifice tangential thereto; a liquid and a rotor therein adapted to form a rotary annular ring of said liquid confined within said casing; means for exploding gas within said annular ring of liquid to forcibly expel said liquid from said casing through said orifice for the purpose of producing power.

8. In an internal combustion motor, a pair of casings, a rotor within each of said casings; a liquid initially within one of said casings; means to explode a gas within that casing containing said liquid to force the liquid into the other casing against the rotor contained therein; means to explode a gas within the latter casing to force the liquid back into the former casing against the rotor

contained therein; the movement of said liquid rotating said rotors with alternate power impulses.

9. In an internal combustion motor: a pair of casings; passageways connecting said casings; a rotor within each of said casings; a liquid within said casings; means to cause said liquid to rotate within said casings, and to flow from one casing to the other casing through said passageways by exploding gas alternately within said casings, the direction of rotation of said liquid within either casing being constant; and the circulating liquid generating power by alternate contact thereof upon said rotors.

In witness whereof I claim the foregoing as my own I hereunto affix my signature, in the presence of two subscribing witnesses, at Portland, county of Multnomah, State of Oregon, this 16th day of Sept., 1918.

ARTHUR L. SMITH.

Witnesses:

D. A. DONELSON,
RALPH E. REID.
